(57) **CLAIM**

The ornamental design for a multifunctional microscope stand, as shown and described.

DESCRIPTION

FIG. 1 is a perspective view of a multifunctional microscope stand showing my new design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a partial enlarged view of FIG. 1;

FIG. 10 is a partial enlarged view of FIG. 1;

FIG. 11 is a partial enlarged view of FIG. 1;

FIG. 12 is a partial enlarged view of FIG. 1;

FIG. 13 is a partial enlarged view of FIG. 2; and,

FIG. 14 is a partial enlarged view of FIG. 2.

The broken lines in the figures are for the purposes of illustrating portions of the multifunctional microscope stand, which form no part of the claimed design.
